Attorney

UNITED STATES PATENT OFFICE.

HOWARD EARL HOOVER, OF CHICAGO, ILLINOIS, ASSIGNOR, BY MESNE ASSIGNMENTS,
TO THE HOOVER COMPANY, OF NORTH CANTON, OHIO, A CORPORATION OF OHIO.

SUCTION CLEANER.

Application filed October 21, 1922. Serial No. 595,900.

My invention relates in general to suction-cleaners and in particular to that type wherein the suction-nozzle is held elevated somewhat above the floor and the floor covering being cleaned is held suspended against the nozzle-lips by air pressure and subjected to the action of means designed to beat and sweep the same.

Prior to my invention, suction-cleaners of this type have been provided either with a rotating element designed to both beat and sweep the floor-covering, or with means designed exclusively to beat the same.

Where a single means is employed to both beat and sweep the floor-covering, a sacrifice in both beating and sweeping efficiency must be made in order to secure both functions in a single unit, and where means designed exclusively for beating are employed, the machine can have but very little sweeping action, which is essential in removing lint and other forms of surface litter.

An object of my invention, therefore, is to provide a suction-cleaner equipped to both beat and sweep a floor-covering in the most efficient manner.

With these and other objects in view my invention consists in the novel construction and arrangement of parts hereinafter described and more particularly pointed out in the claims.

Practical forms in which my invention may be embodied are shown in the accompanying drawings in which—

Figure 1 is a side elevation with parts broken away, of a suction-cleaner embodying my invention;

Figure 2 is a partial section taken on line X—X of Figure 1.

In Figures 1 and 2 I have illustrated a suction cleaner comprising a casing in which is formed a suction-nozzle 10, the fan-chamber 11 communicating therewith through the aperture 12 and a discharge-conduit 13 leading from the fan chamber to a dust collecting bag 14.

Mounted on the casing above the fan-chamber is an electric-motor 15 on the shaft of which is mounted the fan 16 and

a pulley 17 over which is trained a belt 18, preferably made of elastic material, the purpose of which will be described later. The casing is supported upon four wheels 19 in such a manner that the lips of the nozzle

opening are held a substantial distance 55 above the floor.

That part of the casing which forms the suction-nozzle comprises the outer end walls 20, 20, and the inner end walls 21, 21. The inner end walls are each provided with apertures 22 and 23 which receive and act as bearings for the beating element 24 and the sweeping element 25 respectively.

In this embodiment of my invention, the beating element is shown composed of a body-portion 26 upon which are mounted in two helical rows beaters consisting of balls 27 made of metal or other suitable material and secured to the body-portion 26 by means of rigid rods 28. The sweeping element 70 comprises a body-portion 29 upon which are mounted in two helical rows tufts of soft bristles 30, so spaced longitudinally of the body portion that they allow the passage of the beating-balls 27 through the spaces between them. This construction allows the bodies of the beating elements and the sweeping elements to be mounted nearer to each other than would be otherwise possible. 80

Mounted on the beating-element intermediate its ends is a pulley 31 over which a belt 18 travels and by means of which the beating-element is rotated by the electrical-motor. 85

Mounted on each end of the body-portion 26 and situated between the inner and outer end walls of the suction-nozzle is a spur-gear 32 which meshes with an idler-gear 33 rotatively mounted on the inner and outer 90 end walls. The idler-gear in turn meshes with spur-gear 34 mounted on each end of the sweeping-element 35. It will thus be seen that the beating-element and the sweeping-element are operatively connected so 95 that when the beating-element is rotated by means of the motor, a corresponding rotation of the sweeping-element also takes place, and because of the toothed gearing the fixed relative position of the beating 100 and sweeping elements is always maintained and interference with each other is avoided.

I claim:

1. In a suction sweeper, a main casing having a suction mouth, means for drawing a current of air through said mouth, support means maintaining the mouth at a distance above the floor covering to be cleaned,

means for sweeping the floor covering, means for vibrating the floor covering while it is drawn up to the mouth by the air, the sweeping means comprising a rotatable body 5 having separated rows of sweeping elements thereon, the vibrating means comprising a rotatable body having thereon rigidly mounted striking members having fixed orbits of travel, and means producing rotation 10 of the sweeping means and vibrating means in a positive angular relation.

2. In a suction sweeper, a main casing having a suction mouth, means for drawing a current of air through said mouth, support 15 means maintaining the mouth at a distance above the floor covering to be cleaned, means for sweeping the floor covering, means for

vibrating the floor covering while it is drawn up to the mouth by the air, the sweeping means comprising a rotatable body having 20 separated rows of sweeping elements thereon, the vibrating means comprising a rotatable body having thereon rigidly mounted striking members having fixed orbits of travel, the axes of the sweeping and striking bodies separated less than the sum of 25 their overall radii, and means producing rotation of the sweeping means and vibrating means in positive angular relation.

Signed at Chicago, in the county of Cook, 30 and State of Illinois, this 19th day of October, A. D. 1922.

HOWARD EARL HOOVER.
